[57] CLAIM

The ornamental design for a buttock exercise device, as shown and described.

DESCRIPTION

FIG. 1 is a front elevational view of a buttock exercise device showing my new design and the rear elevational view being substantially identical;
FIG. 2 is a left side elevational view thereof;
FIG. 3 is a right side elevational view thereof;
FIG. 4 is a top plan view thereof; and,
FIG. 5 is a bottom plan view thereof.
